DESIGN FOR A RING OR SIMILAR ARTICLE

Max Kronstadt, Brooklyn, N. Y.

Application May 20, 1938, Serial No. 77,302

Term of patent 3½ years

To all whom it may concern:

Be it known that Max Kronstadt, citizen of the United States and resident of Brooklyn, in the county of Kings and State of New York, has invented a new, original, and ornamental Design for a Ring or Similar Article, of which the following is a specification, reference being had to the accompanying drawing, forming part thereof, in which,

Fig. 1 is a developed plan view of a ring embodying my design;

Fig. 2 is a side elevational view thereof formed into a ring; and

Fig. 3 is an end elevational view thereof.

I claim:

The ornamental design for a ring or similar article, substantially as shown.

MAX KRONSTADT.
